[57] CLAIM

The ornamental design for an anchor line scope measuring device, substantially as shown and described.

DESCRIPTION

FIG. 1 is a perspective view of an anchor line scope measuring device showing my new design;

FIG. 2 is a top plan view;

FIG. 3 is a rear elevational view;

FIG. 4 is a front elevational view;

FIG. 5 is a right side elevational view, the left side being a mirror image; and

FIG. 6 is a bottom plan view thereof.

FIG. 1

FIG. 4

FIG. 2

FIG. 5

FIG. 6

FIG. 3
